UNITED STATES PATENT OFFICE.

ARNULFO MENDOZA, OF NORTH BERGEN, NEW JERSEY.

TOOTHPHBRUSH.

Application filed July 2, 1926. Serial No. 120,184.

This invention relates to improvements in fountain toothbrushes.

The primary object of this invention is the provision of an improved fountain tooth brush, of a relatively simple and compact nature, embodying an economical and durable construction which is best adapted to enable an operator to feed a tooth cleansing medium into the bristles of a brush head from a suitable container disposed in the handle of the tooth brush; the improved fountain tooth brush embodying features which renders the same sanitary and prophylactic in character.

10 A further object of this invention is the provision of a novel brush head construction for fountain tooth brushes.

15 A further object of this invention is the provision of a novel valve mechanism for regulating the feed of dentifrice into a fountain tooth brush.

20 A further object of this invention is the provision of a novel handle and frame construction for fountain tooth brushes.

25 A further object of this invention is the provision of improvements in fountain tooth brushes such as set forth in my Patents Nos. 1,432,715; 1,521,783; 1,518,341; and 1,518,342, respectively granted on October 17, 1922; January 6, 1925; December 9, 1924; and December 9, 1924, and embodying improvement thereover in the nature of improved brush head supporting and valve details.

30 35 Other objects and advantages of this invention will be apparent during the course of the following detailed description.

In the accompanying drawings, forming a part of this specification, and wherein similar reference characters designate corresponding parts throughout the several views,

40 45 Figure 1 is a perspective view of the improved fountain toothbrush, showing the same open to expose the dentifrice container in the handle portion thereof.

50 55 Figure 2 is a longitudinal sectional view taken through the casing and main construction of the improved fountain toothbrush, showing details thereof.

Figure 3 is a plan view of the improved toothbrush showing a lid portion thereof open.

55 60 Figure 4 is an enlarged fragmentary sectional view showing improved details of the fountain toothbrush.

Figure 5 is a sectional view taken substantially on the line 5—5 of Figure 4.

Figures 6 and 7 are transverse sectional views taken substantially on their respective lines in Figure 5.

Figure 8 is a perspective view of a novel type of valve used in connection with the fountain toothbrush.

Figure 9 is a transverse sectional view taken substantially on the line 9—9 of Figure 2.

Figure 10 is a fragmentary perspective view of a brush head cap embodied as a part of the fountain toothbrush.

Figure 11 is an end view of the improved cap illustrated in Figure 10.

Figure 12 is an inside sectional view looking towards the front of the cap illustrated in Figure 10, this view being taken substantially on the line 12—12 of Figure 2, without showing the brush head.

Figure 13 is a fragmentary top plan view of the brush head seat of the frame of the improved toothbrush.

Figure 14 is a bottom plan view of the brush head seat and brush head assembled therein, showing the manner in which the brush head cap is slipped into position for retention.

In the drawings, wherein for the purpose of illustration is shown only a preferred embodiment of this invention, the letter A may generally designate the improved fountain toothbrush, which may comprise a frame B; brush head C; and means D to operatively connect a conventional dentifrice container E to the brush. A novel valve construction F is provided for regulating the feed of dentifrice thru the means D into the bristles of the brush head C.

The frame B is preferably of metal construction and comprises the handle portion 15; brush head seat 16; and neck portion 17.

The handle portion 15 and the neck portion 17 are formed in half sections, the same including the lower portions 22 and 23 respectively which are integral with each other and with the seat 16 and wherein a pocket 24^a is provided to receive the dentifrice container E and other details.

To the handle section 15 the complementary handle section 24 is hingedly connected at 25 along one longitudinal edge of the portion 22 of the handle section 15 and extending forwardly at 26 to provide the complementary top half for the neck portion 23. Both the closure 24

and the lower half sections of the handle and neck portions 15 and 17 are pocketed to provide an enclosed compartment when the closure 24 is shut wherein the dentifrice container E and means D are received, as illustrated in Figure 2 of the drawings. It is particularly noticeable that the handle and neck portions are tapered; the handle section 15 tapered from its enlarged rear end 10 towards the neck portion 17; and both the upper and lower half sections of the neck portion 17 tapering from its juncture with the handle portion 15 to intermediate its ends and then tapering at an increasing 15 width to the end thereof adjacent the brush head and brush head seat 16. At its forward end the portion 26 of the neck 17, the same being part of the closure 24, is provided with a retaining flange 31 extending inwardly to 20 provide an end wall for the pocket of the portion 26, rearwardly of which a shoulder of the brush head C is received to retain the brush head in position when the toothbrush is closed, as is illustrated in the drawings, 25 and will be subsequently described.

The brush head seat 16 as is illustrated in Figures 9, 13 and 14 of the drawings, includes the side walls 35 and 36 which are integral with the side walls 37 and 38 of the neck portion 23; the brush head seat walls 35 and 36 converging from adjacent the neck of the frame B forwardly, and at their forward ends the same being connected by an arcuate front wall 39. At the lower edges 35 of the walls 35, 36, and 39, are provided inwardly extending retaining flanges 40, 41, and 42 respectively, defining an elongated tapered opening 45 thru which the back of the brush head C projects and is visible exteriorly of the toothbrush when the parts are assembled. A retaining lip 47 is formed on the upper edge of the front wall 39 of the brush head C in projecting relation inwardly over the lower seat flange 42. Thus the brush head seat construction 16 is of open work formation, providing a pocket within which the brush head may be received as will be subsequently described.

The brush head C includes the body portion 50 of any approved material, such as celluloid, bone, hard rubber, ivory, or any other approved material, and the same is preferably colored in a contrasting relation with the metal or material of the seat 16. This brush head body 50 is provided with tufts of bristles 51 embedded inwardly of the top surface thereof and arranged in any approved formation. The body 50 is flat and at a point 52 intermediate the end thereof of the same is widened and therefrom tapers forwardly at a uniformly decreasing width to the front ends thereof where the same is convexly arcuated. Rearwardly of the widened portion 52 the body 50 of the brush head C has a reduced tapered portion 55

which merges into a substantially annular cross section and is adapted to seat in the neck 17 of the frame B while the portion forwardly of the widened part 52 is disposed within the seat 16 of the frame B.

The body 50 at the under surface thereof is provided with a projecting back 52^a formed by annularly recessing the under surface at the peripheral margins of the body 50, in such a manner that the projection will fit snugly into the opening 45 of the seat 16 when the brush head body is within the seat 16, so that the bottom surface of the body will be exposed from the bottom of the seat 16 in a contrasting and ornamental relation which admits also of utility in that incident to this opening 45 a person may insert a finger to force the brush head from its seat, as is quite obvious.

The brush head body is assembled in the seat 16 by slipping the tapered end thereof into the pocket formed by the seat 16, until the same rests on the retaining flanges 40, 41 and 42 and until the front end thereof is disposed beneath the retaining lip 47; the front end of the body being recessed at 57 to permit such assemblage and to prevent the front end of the body 50 from being accidentally elevated from the seat. The rear portion 55 of the brush head 50 as above mentioned is preferably annular in cross section, as is illustrated in Figure 7, and the same in external diameter is slightly greater than the position to which the walls 37 and 38 of the neck portions 23 will flex, so that said walls 37 and 38 clamp about the portion 55 of the brush head to act as retaining flanges to hold the brush head in its seat, as will be apparent.

As is illustrated in Figures 1, 2, 3 and 4 of the drawings, the portion 55 of the body 50 rearwardly of the widest part 52 of the brush head body is thicker than the part of the body forwardly thereof, that is the same is of higher elevation, and this provides a transverse straight shoulder 60 forwardly of which the retaining flange 31 of the closure 24 engages, when the closure is shut, as is illustrated in Figure 2 of the drawings.

A cylindrical shaped duct 63 extends longitudinally thru the rear end of the body 50 of the brush head C, and axially thru the brush head, having an outlet at the extreme rear edge 64 of the portion 55 of the body 50, and extending inwardly along the axis of the body 50 to a location 65 which is disposed forwardly of the shoulder 60, and at this location the duct 63 has an outlet port 66 on the top surface of the body 50, and within the confines of the tufts of the bristles 51; it being a purpose of the invention to vent dentifrice through this port 66, as will be subsequently described.

As a protection for the rear receiving end of the portion 55 of the brush head body 50

it is preferred to provide a metal ferrule 68, which is provided with an opening 69 therein aligning with the duct 63. The duct 63 at the rear end thereof is larger than along 5 the forward end thereof adjacent the port 66, as is illustrated in Figure 4 of the drawings.

The valve construction F is preferably of metal formation, comprising a tubular main body 70, having a rear enlarged tubular portion 71 and also a forward longer tubular portion 72 of less diameter. The tubular body 70 is adapted to fit forwardly in the duct 63 until the shoulder 74 thereof at the 15 juncture of the enlarged and reduced portions 71 and 72 abuts against the shoulder at the juncture of the different diametered portion of the duct 63 as above described. The tube 70 at the front end thereof is provided with a wall 77 and adjacent said wall is provided with a radially opening port 78 which is adapted to align with the port 66, but which may be placed out of alignment therewith merely by rotation of the tube 70.

25 Means is provided as a part of the valve F to rotate the tube 70 and this means includes a pinlike handle 80 which is radially connected in detachable screw threaded manner at 81 in the tube body 70. The portion 30 55 of the brush head body 50 is transversely slotted inwardly from the top surface thereof at 83 to permit a transverse oscillation of the handle 80 in order to selectively align or place out of alignment the ports 66 35 and 78.

The rear edge 80* of the tubular body 70 terminates within the duct 63 for a considerable distance inwardly from the rear edge 64 of the body of the brush head, to 40 permit the insertion of the forward end of the nozzle D to align the passageway 83 thereof with the passageway 84 provided thru the tubular valve body 70. The special nozzle D is of the type set forth in my 45 patents above referred to, and the same at the rear end is provided with an enlarged connecting portion 85 internally screw threaded at 86 to permit the detachable connection of the screw threaded neck 87 50 of a conventional dentifrice container E of any approved size.

In view of the fact that the port 66 will have to outlet between the various bristles of the brush head and due to the shallow top 55 wall of the body 50 of the brush head, and to prevent the weakening of the same incident to the provision of the duct 63, it is preferred to provide a tubular bristle receiving projection or sleeve 90 upwardly extending integral with the body 50 of the brush head, above the duct 63, wherein a special tuft of bristles 91 may be received in a reinforced and properly secured relation.

60 A special detachable cap 95 for the brush

head C is provided, which includes the side walls 96 and 97 having a connecting top wall 98 and a forward end wall 99. The cap 95 is substantially rectangular in side elevation and is entirely open at the rear end 70 thereof to permit its assemblage on the seat 16 of the brush head, and is open at the bottom thereof to permit the reception of the seat 16 and the brush head C therein. In the forward top corner the cap 95 is cut away 75 to provide a ventilating opening 100 which will increase the sanitary value of the toothbrush and permit a circulation of air thru the cap, while protecting the bristles of the brush from dust and contact with foreign 80 elements.

The cap 95 is formed of stamped metal and the lower margins of the side walls 96 and 97 are stamped to provide internal recesses or grooves 102, and at the lower edges 85 having retaining flanges 103 for receiving therein the seat 16 and the body 50 of the brush head in such manner that the bristles will be protected in a non-cramped position. The front wall 99 may be formed by bending the forward portions of the metal of the side walls 96 and 97 about the front of the cap and securing them in place by means of a special metal clamp 105 which has prongs 106* insertable through slits which may be 90 provided in the material of the said forwardly bent portions of the walls. As to the assemblage of the cap, the same is merely slipped over the front end of the seat 16 100 and the brush head C; the walls 96 and 97 being slightly flexible to clamp against the sides of the seat 16 and brush head C as is illustrated in the drawings, to prevent its accidental detachment. As is illustrated in Figure 14 of the drawings the rearmost 105 marginal portions of the side walls 96 and 97 are bent at 106 inwardly, and adapted to clamp against the rearwardly tapering sides of the neck portion 17 to hold the cap 95 110 in position against forward displacement from the brush head.

As to the manner of assemblage of parts, it is quite obvious that the brush head may be readily pushed into place merely by forward shoving the same into its seat 16. The 115 same may be readily displaced by pushing a finger from the outer side of the seat 16 thru the opening 45 against the back of the body 50 of the brush head. When the brush head C is in place with the valve F 120 assembled therein the special nozzle D may be readily inserted into the rear end of the duct 63 after application of the tube E to the nozzle D has been effected, and then the closure 24 of the frame B may be shut to 125 clamp the various parts of the fountain toothbrush in position for use.

It is notable that the parts of the toothbrush may be disassembled for cleaning, and to this end to disassemble the valve F, the 130

pin lever 80 is disconnected and this permits the rearward slipping of the tube 70 to displace the same from the duct 63 for cleansing. The ferrule 68 is also detachable.

5. Various changes in the shape, size, and arrangement of parts may be made to the form of invention herein shown and described, without departing from the spirit of the invention or the scope of the claims.

10. I claim:

1. In a fountain toothbrush the combination of a brush head including a body portion having upstanding bristles thereon, said body portion having an elongated duct therethrough discharging onto said bristles, a rotatable detachable tube in said duct having a port adapted to be rotated into registration with the port of the body of the brush head, said body of the brush head having a transverse slot thereacross communicating with the tube, and a radially extending pin handle detachably connected with the tube and movable in the slot to permit the rotation of the tube.

2. In a fountain toothbrush the combination of a hollow handle having a neck with a passage opening into the handle, a seat having an open pocket therein carried by the neck and opening into the passage of said neck, a brush head detachably seated in said seat and having a duct opening in the passage of the neck, a rotatable tube in said duct, said tube having a side port therein registrable with a port in the brush head, means for rotating said tube to open or close said port with respect to the brush head, a detachable coupling communicating with the tube in the brush head, and a dentifrice container detachably connected with the nozzle and disposed within the handle.

3. As an article of manufacture a brush head comprising a main body portion having upstanding bristles thereon, said body portion having a duct formed longitudinally therethrough and having a port extending transversely therethrough from the duct into a space between said bristles, a sub-

stantially tubular projection formed rigid on the body of the brush head directly above said duct, and a tuft of bristles anchored in said tubular projection.

4. As an article of manufacture a brush head comprising a main body portion having upstanding bristles thereon, said body portion having a duct formed longitudinally therein and having a port extending transversely from the duct into a space between said bristles, a substantially tubular projection formed rigid on the body of the brush head directly above said duct, a tuft of bristles anchored in said tubular projections, a valve tube rotatable in said duct having a port transversely therein, and means for rotating said tube to place the port thereof into or out of alignment with the port of the body of the brush head.

5. In a toothbrush the combination of a brush comprising a rigid body having tufts of bristles extending from the top thereof, said body having an elongated duct extending therein from the rear end thereof to a point intermediate the ends thereof, said body at the front end of said duct having a transverse port opening onto the bristles, a hollow metal tube shorter in length than the length of said duct rotatably disposed entirely within the duct and at the forward end thereof having a transverse port, the rear of said tube terminating within the duct inwardly of the rear edge of the body of the brush head, said body transversely therethrough having a slot intersecting the duct, a detachable handle pin connected with the tube movable in said slot, a ferrule over the rear end of the body of the brush head having an opening therethrough aligning with the duct in the body of the brush head, and a hollow dentifrice tube coupling having a tubular portion adapted to be inserted in the rear end of the duct of the body portion of the brush head into abutting engagement against the rear end of the tube to align the coupling with the tube passageway.

ARNULFO MENDOZA.
